PAUL HUNGERBÜHLER, OF OBERWIL, SWITZERLAND, ASSIGNOR TO LANDIS & GYR,
A.G., A JOINT-STOCK COMPANY OF SWITZERLAND

HOROLOGICAL MECHANISM

Application filed October 12, 1927, Serial No. 225,735, and in Switzerland October 26, 1926.

- The invention relates to horological instruments, and more especially to novel and useful improvements in the construction of clock-mechanisms and their regulating means whereby either a spring balance or a pendulum regulator may be optionally used in assembling or may be interchanged later with a particular or standard construction of clock mechanism.
- 10 Objects and advantages of the invention will be set forth in part hereinafter and in part will be obvious herefrom, or may be learned by practice with the invention, the same being realized and attained by means 15 of the instrumentalities and combinations pointed out in the appended claims.

The invention consists in the novel parts, constructions, arrangements, combinations and improvements herein shown and described.

20 The accompanying drawing, referred to herein and constituting a part hereof, illustrates one embodiment of the invention, and together with the description, serves to explain the principles of the invention.

Of the drawing:—

Fig. 1 is a fragmentary vertical elevation of a portion of a clock mechanism, with the near frame plate removed, exemplarily embodying a spring balance controlled escapement, and is taken substantially on the line 1—1 of Fig. 2;

Fig. 2 is a fragmentary side elevation, looking at Fig. 1 from the right;

35 Fig. 3 is a fragmentary rear elevation corresponding to the upper right-hand part of Figs. 1 and 2;

Fig. 4 is similar to Fig. 1, except that it shows a pendulum regulator in place of the spring balance regulator, and is taken on the line 4—4 of Fig. 5;

Fig. 5 is a fragmentary side elevation, with parts in section, looking at Fig. 4 from the right; and

45 Fig. 6 is a fragmentary rear elevation corresponding to the right-hand part of Figs. 4 and 5.

The invention is directed primarily toward securing interchangeability, simplicity, uniformity, facility and economy in the con-

struction and assembling of horological instruments, and more especially in clock mechanisms; one of the principal objects being to provide a clock mechanism of standard design and size, and optionally useable balance 55 or pendulum regulating means which may be assembled with the clock mechanism, or which may be later interchanged without disassembling or otherwise disturbing the clock mechanism. A further object of the invention is the provision of means for speedy and accurate regulation of the clock movement, whether equipped with a spring balance or pendulum regulator, so that it may be reliably and accurately regulated within a very 60 brief period of observation and adjustment for this purpose.

The optional interchangeability of spring balance or pendulum regulating means is preferably realized through mounting the 70 regulating mechanism in its own frame, structurally independent of the clock mechanism, and providing means for accurately and permanently correlating the intervening driving connection with both mechanisms. 75 The frame for the regulating mechanism is attached to the clock frame and preferably on the exterior thereof. This object is effected in the exemplified embodiment by providing the interposed drive between the clock 80 movement proper and the regulating mechanism with at least one bearing of an arbor in the frame of the regulating mechanism, with cooperating means for nicely adjusting and correlating the connection of this intervening driving means with the clock mechanism. The frame structure is likewise shaped so that the connecting drive may be slipped 85 into the clock mechanism and the regulating device accurately positioned and fixed in place.

The means for effecting the speedy and at the same time accurate and reliable setting of the regulating mechanism comprises 95 a member having a cycle of movement which is completed within a relatively brief period of time, and cooperating indicating means for indicating relatively very brief periods of time with respect to the cycle of said moving means. As embodied, a rotating hand 100

or dial is provided, making its circuit within one minute, or other comparatively brief time interval, and cooperating therewith indicating means for measuring the movement 5 of said moving part in fractions of a second. Thus the variations of the mechanism from absolutely correct time are almost immediately apparent, on a relatively large scale, and thus the regulation may be effected 10 with unusual brevity and certainty.

In Figs. 1, 2 and 3 of the drawing there is illustrated and exemplified an embodiment 15 of the invention with a spring balance regulator device; and in Figs. 4, 5 and 6 there is shown an exemplary embodiment of the invention with a pendulum mechanism.

Referring now by way of example to the exemplary embodiment of Figs. 1, 2 and 3, the flat and parallelly disposed frame plates 20 1 and 2 of the clock mechanism are shown with the spacing and binding rods 12. The illustrated parts of the driving train of the clock, as embodied, comprise an arbor 3, journaled in the frame plates, with a driven pinion 4 and a driving gear 5 fixed on the arbor. Gear 5 meshes with a pinion 6, fixed on an arbor 7, likewise journaled in the frame plates. A gear-wheel 8, fixed to pinion 6, meshes with a pinion 9 on an arbor 10, journaled 25 in like manner in the frame plates. Fixed on shaft 10 also is a gear-wheel 11, which is the driving element of the clock mechanism for the regulator mechanism of either type of regulating mechanism.

30 35 In accordance with the present preferred embodiment, a connecting driving element is provided, having at least one bearing in the regulating mechanism and which may be slipped into the assembled clock mechanism 40 without mechanical disturbance or disarrangement. This connecting element, as embodied, has a pinion 20, meshing with the driving gear 11 of the clock, and a driving element such as a gear 21 connecting with the usual mechanism of the spring balance 45 escapement. The pinion and gear are fixed to rotate together on a shaft or arbor 22, the axis $x-x$ of which may be brought into accurate alignment with the clock mechanism 50 while being maintained in fixed relation to the escapement mechanism.

The escapement mechanism is provided with a separate frame or casing, affixable to the flat frame plate 2 of the clock mechanism 55 and preferably on the outside thereof, as shown in the drawing. For the purpose of slipping pinion 20 and shaft 22 into the clock mechanism without disturbance, a recess 27 is formed in the frame plate 2, extending 60 from an outer edge of the plate sufficiently far to include the axis $x-x$ of the shaft 22. The shaft 22 has one end thereof journaled in the frame of the casing 29 of the escapement mechanism, and the other end thereof 65 is journaled in a bracket 30, fixed to and pro-

jecting from the inner frame plate 31 of the escapement mechanism, and extending inwardly through the aperture 27 in the clock frame plate 2, whereby the pinion 20 is positioned in mesh with its driving gear 11. As shown, gear-wheel 21 is in mesh with a pinion 35, fixed on a shaft 36, having its inner end likewise journaled in the bracket 30, and the other end thereof journaled in the frame of the escapement mechanism. This 70 shaft may be fixed directly to the escapement wheel 32 of the escapement mechanism, and the escapement wheel 32, anchor 33, hair-spring 34, and associated parts of the escapement mechanism may be of any known 75 or other suitable construction. The regulator arm 37 and its scale 38 are mounted on the rear of casing 29 of the escapement.

The form of mechanism for rapid and accurate regulation of the clock, preferably 80 employed in connection with this embodied form, comprises a circular scale 41 fixed to the outer face of the gear 21, which gear extends partly outside the casing 29, as will be clear from the drawing. The disc 41 as embodied completes its rotation in one minute, and is graduated in seconds. An index line 42 is marked on the rear face of the frame plate 2 in operative relation therewith. Thus, any deviation of the clock mechanism during an elapsed minute will be indicated clearly in fractions of a second by this mechanism, and thus the regulation may be effected 90 very rapidly and very accurately.

Referring now in detail to the embodied 95 form of mechanism in Figs. 4, 5 and 6, illustrating exemplarily the application of the invention to a pendulum regulator, the frame and parts of the driving train of the clock mechanism may be the same as already shown 100 and described, and they are indicated in these figures by the same reference numerals.

As embodied, this mechanism comprises a shaft 51, concentric with the axis $x-x$, and fixed thereto is a pinion 52, meshing with and 105 driven from the gear-wheel 11. Fixed also to shaft 51 is the escapement wheel 53. The rear end of arbor 51 is journaled in the clock frame plate 1, and the forward end thereof is journaled in the frame plate 54 of the pendulum mechanism, which plate 54 is in contact with the clock frame plate 2 and is supported thereon by means 110 later to be described. Fixed to the frame plate 54 are outwardly-extending, side-by-side bracket plates 57 and 58, between which is supported the pendulum 59, which may be of known or other suitable construction and need not be described in detail. The pendulum fork 61 has its lower forked end 62 115 embracing the pendulum rod. The fork farther up is bent inwardly, passing through an aperture 63 in the plate 54 and through the opening 27 in plate 2, and has a hub 64 fixed on a shaft 65. Shaft 65 is journaled at one end 120 125

in the frame plate 54 of the pendulum mechanism and at the other end in the frame plate 1 of the clock. Fixed also on shaft 65 is the anchor 71, carrying the pallets 72 and 73, which cooperate in the usual manner with the escapement wheel 53.

The embodied form of regulating means cooperating with the mechanism just described, comprises a hand 75 fixed on the exterior end of shaft 51, outside of and in close proximity to the pendulum frame plate 54. On the frame plate, is marked a circular scale 76, preferably marked in seconds, and the hand 75 makes a complete rotation in one minute. Thus any variations of the clock mechanism are indicated in fractions of a second during each recurring minute, and the speedy and reliable regulation of the mechanism may thereby be effected through the usual compensating devices of the pendulum.

In the embodied form of means for correlating and adjusting the position of the connecting shaft between the clock mechanism and the regulator, the axis of which is indicated by the line $x-x$, a slot 81 is formed in one side of the recess 27 in the frame plate 2. Mounted also in the frame plate 2 by a tight friction fit is a disc 82, provided with a squared turning portion 83. Eccentrically positioned in the disc 82 is an aperture 84. Fixed to and projecting from the rear of the frame plate 54 of the pendulum mechanism, and in like manner from the rear of the frame plate of the spring balance escapement mechanism are pins 85 and 86, adapted to project respectively into the slot 81 and into the hole 84 in the disc 82. Thus by turning the disc, the shaft 22 or the shaft 51, as the case may be, represented by the line $x-x$, may be brought into the desired nice relation to the driving gear 11.

Screws 89, or other suitable fastening devices, are employed for holding the regulating device in the adjusted position already described, and the parts are combined and proportioned so that one or more of these devices may be used whether the regulator be a spring balance or a pendulum.

The invention in its broader aspects is not limited to the specific mechanisms shown and described but departures may be made therefrom within the scope of the accompanying claims without departing from the principles of the invention and without sacrificing its chief advantages.

What I claim is:—

1. In combination, a clock movement including a gear train and a frame, said frame being provided with an inwardly recessed portion, a regulating mechanism having a separate frame, means for connecting said regulating mechanism with the gear train, and means for fastening the regulating mechanism to the clock frame.
2. A clock movement having regulating

mechanism and adapted to be controlled by means of a balance wheel or pendulum and including a gear train, a frame in which said gears are journaled, said frame being provided with an inwardly recessed portion to receive the regulating mechanism, means for fastening the regulating mechanism to the frame, and bearings in said frame oppositely disposed to said recess for rotatably journaling a part of one of the regulating mechanisms which may be employed as a part of the clock mechanism.

In testimony whereof, I have signed my name to this specification.

PAUL HUNGERBÜHLER.
